UNITED STATES PATENT OFFICE.

JOHN FRANKLIN, OF NORWOOD, OHIO.

ANTIVIBRATORY SUPPORT FOR GAS-BURNERS.

SPECIFICATION forming part of Letters Patent No. 665,082, dated January 1, 1901.

Application filed January 15, 1900. Serial No. 1,477. (No model.)

To all whom it may concern:

Be it known that I, JOHN FRANKLIN, a citizen of the United States of America, and a resident of Norwood, in the county of Hamilton and State of Ohio, have invented certain new and useful Improvements in Antivibratory Supports for Gas-Burners, of which the following is a specification.

This invention relates to certain improvements in antivibratory supports for gas-burners, being especially adapted for overcoming vibration in street and factory gas-lamps, so as to prevent damage to the frail incandescent mantles commonly used upon such lamps; and the object of the invention is to provide a device of this character which shall be of a simple and inexpensive nature and not liable to become deranged or broken when in use.

The invention consists in certain novel features of the construction, combination, and arrangement of the several parts of the improved antivibratory supporting device, whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate the invention, Figure 1 is a view drawn to a small scale and showing a burner having a support constructed according to my invention. Fig. 2 is an enlarged sectional view taken axially through the device. Fig. 3 is a section taken transversely through the device in the plane indicated by line *a a* in Fig. 2. Fig. 4 is a view showing, detached and enlarged, the form of spring preferably employed. Fig. 5 is a view drawn to a small scale and showing the employment of the improved device in connection with an ordinary street-lamp. Fig. 6 is an enlarged fragmentary view showing a form of cock and lighting device especially adapted for use on street-lamps. Fig. 7 is a view drawn to a small scale and showing the employment of the improved antivibratory support in connection with a suspended or hanging factory-lamp. Fig. 8 is a view showing a modified form of the antivibratory support especially adapted for use in connection with suspended lamps such as

that shown in Fig. 7. Fig. 9 is a section taken axially through the device shown in Fig. 8.

Referring, primarily, to Figs. 1 to 4, 1 indicates the gas-supply pipe, and 2 indicates the cock controlling the flow of gas through the same. 3 indicate burners supplied from the pipe 1 and carried on arms 4, extended from opposite sides of a burner connection 5, between which and the cock 2 is arranged the improved antivibratory support, (indicated as a whole by 6.) The burners 3 may be of any preferred kind, being usually of the Bunsen type, having incandescent mantles suspended above them in a well-known way, and there may be but one or any number of burners 3 instead of two such burners, as herein shown. The device 6 comprises, as shown in the sectional view, Fig. 2, a cup-shaped part or receptacle 7, having a threaded socket 8 at its base to receive the threaded upper end of the gas-pipe and provided with a vertical tubular stem 9, extending up from its center, said stem having its upper end open and its lower end adapted to receive gas from the gas-pipe when the latter is screwed in the socket 8. The stem 9 extends up above the top of the receptacle 7 and forms between itself and the walls of the receptacle an annular space or chamber 10, adapted to hold a supply of mercury, as indicated at 11, the upper edge or top of the receptacle-wall being, by preference, formed with an upturned annular flange 12, having an inwardly-directed annular lip 13, encircling the mouth of the chamber 10 and adapted to prevent the escape of mercury from said chamber 10 in case the device should be violently struck or shaken. The receptacle-wall is also formed at its upper part with a horizontally-projecting annular flange 14, to which are held at suitable points by means of screws 15 or the like the arms 16 of a sheet-metal spring, preferably constructed, as shown in Fig. 4, of a single piece 95 of sheet metal—such as copper, brass, or other material not readily oxidized—and comprising a circular centrally-perforated body portion 17, having four integral diverging arms. The central aperture of the body 17 of the spring 100 serves for the passage of the threaded upper end 18 of a tube 19, which screws into the lower part 21 of the burner connection 5 and has formed on it below its screw-threaded

part an annular flange, between which and the under side of the burner connection 5 the body portion 17 of the spring is clamped. In this way it will be seen that the burners 3 3 5 are held elastically supported over the receptacle 6, with its gas-passage communicating with the bore of the tube 19.

The lower end of the tube 19 extends down around the stem 9 of the receptacle 7, which 10 stem is thereby housed within the tube in the bore 20 thereof, as clearly shown in Fig. 2, a sufficient space being provided between the two parts to permit free movement independent of one another. The end of the tube 19 15 is also of such a length as to dip in the mercury 11, held in the chamber 10 of the receptacle, so that a seal is formed between the tube 19 and stem 9 in such a way as to prevent the escape of gas from the gas-passage 20 of the stem, such gas being thus caused to pass through the bore 20 of the tube 19 up into the burners 3 above the same. By this construction it will be seen that when the 25 parts are assembled the spring-arms 16 will afford a yielding or elastic support for the burner and will act as a cushion between the same and the gas-pipe, so that the vibrations and jarring of the pipe will be received and neutralized by said cushion and will not be 30 transmitted to the burner, as is the case in lamps constructed in the ordinary manner. In this way it will be seen that the extremely-frail incandescent mantles used upon the burners are protected against injury from 35 sudden jars and vibration, and the cost of maintaining the burner is thereby materially lessened. It will also be seen that the arrangement of the tube 19 with its lower end inclosing the stem 9 of the receptacle acts as 40 a stop to prevent excessive swaying movement of the burner upon its elastic support, whereby damage to the spring-arms themselves is avoided, and, furthermore, the mercury held in the chamber 10 acts not merely 45 as a seal to prevent the escape of gas between the tube 19 and the stem 9, but also serves to check the vibration of the burner upon its elastic supports.

In Fig. 5 I have shown the application of 50 the improved antivibratory support to an ordinary street-lamp. In this view, 22 indicates the lamp-post, and 23 the globe inclosing the burners, which latter may be of the kind shown in Fig. 1 and provided with incandescent mantles *m*. The improved antivibratory support is arranged between the gas-cock 2 and the burner connection 5, as in the previous case, and serves to prevent the mantles from being broken or damaged when the 55 post 22 vibrates or is shaken by the wind or from any other cause. In connection with street-lamps I prefer to use a gas-cock and lighting device, as shown in Fig. 6, the cock 2 being provided with an auxiliary gas-passage leading to a tip 24, extended up at one 60 side of the antivibratory support and of the

burner or burners, as indicated in Fig. 5, and adapted to be lighted before gas is supplied to the burner itself. The burner or burners are by the antivibratory support flexibly or 70 movably connected with the tip 24, and are consequently capable of free movement upon their support relatively to the said auxiliary tip. The cock 2 is a three-way cock and when turned first supplies gas to the auxiliary tip 24, to which a match or torch may be applied, causing the gas escaping at said tip to burn in a long jet beside the burners 3. Upon further turning movement of the cock 2 the gas is turned on to the burners 3 and is 75 cut off to the auxiliary tip 24, so that the jet from said tip 24 before being extinguished will serve to ignite the gas at the burners. In this way the mantles are further protected from injury, since the cock and auxiliary tip 80 24 being flexibly or movably connected by the antivibratory support with the burner the gas may be turned on or off without danger of unduly jarring the mantle, and the lighter is not required to apply his torch or match to 85 the burner itself, but merely to the auxiliary tip 24, and consequently the risk of damage to the mantles from contact with a match or torch or from jarring is greatly lessened.

In Figs. 7, 8, and 9 I have shown a modified form of the device especially adapted for use in connection with hanging lamps such as shown in Fig. 7. In this form the antivibratory device comprises two parts 25 and 26, connected, respectively, to the gas-pipe 1 and 90 to the lamp 27, the lower part 26 having an upturned barrel-like flange 30 and inside said flange, a tubular stem 31, an annular space or mercury-chamber 32 intervening to receive the depending tube 33 of the upper member 105 or part 25.

Mercury in chamber 32 forms a seal to prevent the escape of gas between the two parts, and said parts are movably connected by bent springs 28, extending between them. 110 Chains 29 or other like devices also connect the parts 25 and 26, so that in case of breakage of the springs 28 the burner 27 will be supported against falling. If desired, also, the mouth of the mercury-chamber 32 may be 115 formed with an annular inturned lip similar to the lip 13, above described; but owing to the depth of said chamber 32 such a lip is not altogether essential.

From the above description it will be seen 120 that the improved antivibratory support is of an extremely simple and inexpensive construction and is especially well adapted for use in connection with gas-lamps having incandescent mantles, since it minimizes the 125 vibrations and jars which would otherwise be transmitted direct to the burner and its mantle, and thereby prevents damage to the mantle and greatly reduces the expense of maintaining the lamp. It will also be obvious from the above description of the invention 130 that the device is capable of considerable

modification without material departure from the principles and spirit of the invention, and for this reason I do not wish to be understood as limiting myself to the precise form and arrangement of the several parts herein set forth.

Having thus described my invention, I claim—

1. A device for overcoming vibration in gas-burners comprising a burner connection, a tubular part screwed into said connection, a spring formed with a body portion held between the burner connection and the tubular part and provided with diverging arms integral with said body portion, a part to which the arms of the spring are connected and which is adapted for connection with a gas-pipe and has a gas-passage adapted for communication with the bore of said tubular part, and means for preventing the escape of gas between the two parts, substantially as set forth.
2. An antivibratory support for gas-burners and the like comprising two parts formed with corresponding gas-passages and a strip of spring material having its central portion secured to one of said parts and its end portions formed into spring-arms each extended across the space between the two parts of the

support and secured to the other part of the support, substantially as set forth.

3. An antivibratory support for gas-burners and the like comprising two parts having corresponding gas-passages and a strip or piece of spring material having at its central portion a perforation, a hollow plug passed through said perforation and engaged with one part of the support for holding the central portion of the strip thereto, the end portions of said strip being formed into spring-arms each extended across the space between the two parts and secured to the other part of the support, substantially as set forth.

4. A device of the character described comprising a gas-cock, a main gas-burner and an auxiliary tip having independent gas connections whereby each is supplied with gas through said gas-cock, and an elastic supporting means whereon the main gas-burner is held for movement relatively to the said auxiliary tip, substantially as set forth.

Signed by me at Cincinnati, State of Ohio this 13th day of January, 1900.

JOHN FRANKEN.
